UNITED STATES PATENT OFFICE

126,704

DESIGN FOR A TEXTILE FABRIC

Charles H. Kohnken, New York, N. Y.

Application December 27, 1940, Serial No. 97,632

Term of patent 3½ years

To all whom it may concern:

Be it known that I, Charles H. Kohnken, a citizen of the United States of America, residing in New York city, county of New York, and State of New York, have invented a new, original, and ornamental Design for a Textile Fabric, of which the following is a specification, reference being had to the accompanying drawing, forming part thereof, wherein,

Figure 1 is a front view of a textile fabric showing my new design.

Figure 2 is a rear view of the textile fabric shown in Figure 1.

The characteristic features of my design for a textile fabric comprise the raised and depressed stripes on the face and on the back thereof, said stripes being of the specific widths and arrangement as shown.

I claim:

The ornamental design for a textile fabric, substantially as shown and described.

CHARLES H. KOHNKEN.
